UNITED STATES PATENT OFFICE.

ROBERT A. FORESMAN, OF ESSINGTON, PENNSYLVANIA, ASSIGNEE TO WESTINGHOUSE ELECTRIC AND MANUFACTURING COMPANY, A CORPORATION OF PENNSYLVANIA.

UNDERFEED CHAIN-GRAVE STOKER.

Application filed October 14, 1920. Serial No. 416,903.

To all whom it may concern:

Be it known that I, ROBERT A. FORESMAN, a citizen of the United States, and a resident of Essington, in the county of Delaware and State of Pennsylvania, have invented a new and useful Improvement in Underfeed Chain-Grate Stokers, of which the following is a specification.

My invention relates to mechanical stokers and more particularly to stokers of the underfeed type employing a chain grate mechanism, and has for an object to combine in one stoker elements whereby the advantages of both the underfeed and of the chain grate types of construction are attained.

A further object is to produce a stoker which shall be adapted to handle fuels of various types to obtain the greatest amount of heat energy therefrom, together with ease of installation and maintenance.

These and other objects attained will be more manifest in the description given in the following specification in which Fig. 1 is a side view, partially in section and partially in elevation of a stoker embodying my invention, Fig. 2 is a plan view and Fig. 3 a detail sectional view on line III—III of the apparatus shown in Fig. 1.

In my improved stoker device, I provide a chain grate stoker utilizing the underfeed principle, thereby gaining the advantages of each of the above well known types of stokers. The grate is composed of a series of movable sections, alternate sections being elevated above the adjacent sections, thus forming a trough or retort into which fuel is fed from a hopper by an associated ram, reciprocating in the forward portion of the trough. In a stoker of this construction, fuel is fed into the retorts from beneath and allowed to bank in the forward portion of the retort where it has ample time to coke, thus permitting the underfeed principle to be fully utilized. The elevated chain section is open throughout its length, thus forming air admitting surfaces corresponding to tuyère sections and the lower chain section, which is covered at its forward portion, constitutes a base portion for the retort. By this construction, I obtain an even distribution of fuel regulated in such a manner that complete combustion is obtained and the ash disposed of without the use of dump grates or auxiliary means. By forming the grate in sections of uniform size, I

readily construct a grate adaptable to any size of furnace, in accordance with the unit principle.

Referring to the drawings for a more detailed description, I show a hopper at 10, opening at its lower portion into a trough 11 in which reciprocates a plunger 12, this plunger being operated in any convenient manner. The fuel is fed through the trough 11 over a raised portion 13, from which it is carried by moving chain grate sections 16 and 19. Plates 15 upon which rests the upper portion of the elevated chain section 16, form the sides of the stationary portion of the retort and a plate 14 forms the bottom portion thereof.

Power is transmitted to the grate sections through shafts 17 and 18, respectively. The lower chain section 19 travels beneath the bottom plate of the stationary portion 14 of the retort. Air is delivered, under pressure, to the grate from air boxes 20. At the rearward portion, sprocket wheels carrying the chain grate sections revolve about a common shaft 21 and the entire grate structure may be uniformly operated by applying power to the single shaft 21. The stoker as a unit is readily movable on wheels 22 and 23 if for any reason it must be removed from the furnace.

Having thus described the arrangement of a stoker embodying my invention, the operation thereof is as follows: The shaft 21 is driven continuously by means, not shown, such for example as a separate electric motor or by connections to the ram-operating device, although it is preferable that the speed of this shaft may be subject to independent, ready and wide control as determined by the rate of combustion of the fuel burned in the furnace. When the ram 12 is reciprocated by any suitable means and air supplied to the chamber 20, fuel is forced from the hopper 10 over the plate 14 into the retort situated between the low chain 19 and the two immediately adjacent high chains 16. Air is supplied to the fuel through the high chains 16 and combustion ensues in the usual manner for an underfeed furnace, as by coking, etc., as is well understood in the art.

For rapidly burning fuels, such as those having a high gaseous content, the chains 16 and 19 are operated at relatively high speed so that by the time the fuel is con-

sumed, the residue has reached the back of the furnace.

If, on the other hand, the fuels have a relatively low gaseous content and are of slow combustion rate, the chains are moved somewhat more slowly in order that unburned fuel shall not be discharged at the rear of the furnace.

I have shown a furnace made up of alternate elevated and depressed chain sections, as shown more clearly in Figs. 2 and 3, but obviously this arrangement may be varied in that two or more depressed chain sections might be separated by single elevated chain sections or by two or more elevated chain sections, all as dictated by the size desired for the retorts and for the tuyères with respect to the most desirable chain widths to be used.

20 In this same connection, the extreme adaptability of my furnace construction to fire boxes of different sizes should be pointed out. The various chain belts are of uniform width and carried on interchangeable sprocket wheels, these sprocket wheels in turn being mounted on shafts which may be made of any length. Thus the total grate may be of any desired overall width and this overall width may be portioned off into a greater or less number of retorts as dictated by the specific operating conditions. Furthermore, the ratio of the retort width to tuyère width may be readily changed as for the consumption of a radically different type of fuel.

With a given furnace installation, by the independent adjustment of the ram speed, of the belt velocity, and of the air pressure, an extremely wide adjustability is provided, as demanded by different types of fuel.

While I have shown my invention in but one form, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

What I claim:—

1. In a stoker comprising a fuel feeding mechanism, retorts having portions of progressively diminishing depth, said retorts being partially defined by chain grate sections of which certain sections are elevated above the others at one end.

2. A mechanical stoker comprising a plurality of chain grate sections arranged to define the bottom and the upper edges of a retort and an underfeed device communicating with the retort.

3. A mechanical stoker comprising fuel-feeding mechanism including a trough and a plurality of chain grate sections defining

the bottom and the upper edges of a retort, the trough extending into the retort for supplying fuel thereto.

4. A mechanical stoker comprising fuel-feeding mechanism including a trough, a retort chain grate section partly underlying the trough, and tuyère chain grate sections arranged at the sides of the retort chain grate section, and defining therewith the top edges and the bottom of a retort, said trough being arranged to discharge fuel into the retort. 70 75

5. A mechanical stoker comprising a fuel-feeding mechanism and series of chain grate sections, certain of said chain grate sections being elevated at their forward ends, others of said chain grate sections being of relatively lower elevation at their forward ends in order to define the top edges and the bottoms of retorts, said chain grate sections being at equal elevation at their rear ends. 80 85

6. An underfeed stoker apparatus comprising a fuel-feeding mechanism, and movable chain grate sections, two chain grate sections being of higher elevation at their forward ends than an intermediate chain grate section, and the fuel-feeding mechanism being arranged to deliver fuel between said elevated chain grate sections. 90

7. An underfeed stoker comprising a hopper, a trough communicating with the hopper, a fuel-feeding mechanism associated therewith, a grate composed of movable chain grate sections of different lengths and of different elevations at their forward ends to define the bottoms and the top edges of retorts, the longer chain grate sections being at the higher elevation, and a stationary guide member overhanging the forward portion of the shorter chain grate section and 100 connected to the trough. 105

8. In a mechanical stoker, fuel-feeding mechanism, movable chain grate sections, adjacent sections being of different elevation at their forward ends and of equal elevation 110 at the rearward ends so as to define the bottoms and the top edges of retorts, and an air supply chamber located beneath the chain grate sections to supply air thereto. 115

9. An underfeed stoker comprising fuel-feeding mechanism and movable chain grate sections, certain of the sections being elevated above the others to form upper and bottom portions of fuel-receiving retorts. 120

10. An underfeed stoker, comprising fuel-feeding mechanism and movable chain grate sections arranged to form portions of retorts, alternate chain grate sections being elevated above the adjacent chain grate sections, the elevated chain grate sections forming the tuyères and the depressed chain grate sections forming at least in part the bottoms of the retorts. 125

11. In an underfeed stoker comprising fuel-feeding mechanism, a series of chain 130

grate sections arranged to define upper and bottom portions of retorts, said chain grate sections being interchangeable to add to or diminish the size of the grate.

5 12. In an underfeed stoker, hoppers, troughs communicating therewith, fuel-feeding mechanisms in the troughs, a series of chain grate sections arranged to partially define retorts, certain of said chain grate sections being elevated to form tuyères and other of said chain grate sections being depressed to form movable bottom portions of the retorts, and stationary members extend-

ing over the forward portions of the depressed chain grate sections to form stationary bottom portions for the retorts. 15

13. An underfeed stoker comprising alternately disposed tuyère sections and retort sections, said tuyère sections embodying endless chain units, and said retort sections embodying endless chain units at a lower elevation than said tuyère chain units. 20

In testimony whereof, I have hereunto subscribed my name this eleventh day of October, 1920.

R. A. FORESMAN.
